UNITED STATES PATENT OFFICE

2,543,217

SEALED MAILBAG SECURING DEVICE

Frederick W. Wolf, Chicago, Ill.

Application April 25, 1947, Serial No. 743,838

3 Claims. (Cl. 292—307)

1

My invention relates to securing devices for mail bags, to keep them closed after they have been filled, and one object is to provide a device of this character which secures a strong grip on the rope sections which project from the bag, whereby to firmly maintain the closed condition of the same.

A further object is to devise an article of the above character which is also conducive to the application of a seal to prevent tampering with the securing device.

Another object is to design the novel device along sturdy and compact lines, so that it may be handy to use and durable over a long period.

With the above objects in view, and any others which may suggest themselves from the description to follow, a better understanding of the invention may be had by reference to the accompanying drawing, in which—

Fig. 1 is an elevation of the top portion of a typical mail bag, showing the application of the securing device;

Fig. 2 is a perspective view of the device, with the rope sections passing through it;

Fig. 3 is a perspective view of the seal;

Fig. 4 is a bottom view of Fig. 2;

Figs. 5 and 6 are, respectively, enlarged sections on the lines 5—5 and 6—6 of Fig. 2, Fig. 6 showing the seal in process of application;

Fig. 7 is a view similar to Fig. 6, showing the seal secured; and

Fig. 8 is a section on the line 8—8 of Fig. 2.

Referring specifically to the drawing, 15 shows a typical mail bag whose mouth 16 has been gathered by a draw rope 17 to close the bag. The sections 18 of the rope extending from the bag are applied to the securing device 20 in the manner shown in Fig. 2.

The securing device 20 is formed in two major parts, the part indicated at 20 being a rectangular channel of heavy sheet metal. The other part is also a channel 21 of similar form, but shorter. Also, the channel 21 is designed to apply in inverted position to the channel 20 and is slightly narrower than the same to slidably fit therein from the bottom, as shown in Fig. 6.

The channel 20 is formed with a group of four openings 23 arranged in square formation. Thus, the rope sections 18 extending from the mail bag are designed to enter the channel by way of one pair of openings 23 and emerge by way of the other pair, as clearly shown in Figs. 2 and 8. It is noted in the latter figure that the channel top is depressed at 25 between the said pairs of openings and also at 26 beyond such pairs in order to

create a curved guide for the passage of the rope sections and save them from becoming cut or frayed by the edges of the openings. The top of the channel 20 is also cut with a cross-slot 28 at a point beyond the issue zone of the rope sections 18, as shown in Figs. 2 and 5.

The channel 21 is made with an inward flange 30 at one end; and the sides 31 of the channel are joined to the sides 32 of the channel 20 by a cross-pin 34 having terminal heads 35. The cross-pin is a short distance inwardly of the flange 30 and forms a pivotal joint between the two channels.

The channel 21 is formed with a large rectangular opening 37 at a medial point, a tongue 38 being struck inwardly in forward direction from such opening. As shown in Figs. 4 and 5, the direction of the tongue 38 is cross-wise of the internal portions of the rope sections 18; and the tongue engages such sections with a clamping pressure and at forward angle, so as to lock the sections from being drawn back, that is, in the direction indicated by the arrows in Fig. 5.

Constituted as just described, the securing device permits the rope sections 18 to be drawn forwardly through the openings 23, whereby to draw the bag close to the device, the tongue 38 then functioning as described to maintain the fastening in place. However, this is only possible when the channel 21 remains in closed relation within the channel 20.

Means are provided to lock the channel 21 in the closed position, such means originating with a frontal tongue 40 bent inwardly from the channel 21. As shown in Figs. 5 and 6, the tongue 40 is of length to pass through the slot 28; and the tongue is positioned midway between the sides of the channels. As noted in Fig. 6, the tongue 40 is slotted in its side edges as indicated at 42 to define a headpiece 43. Fig. 3 shows a strip of steel or plastic material designed to serve as a seal between the channel 20 and the tongue 40. Thus, the seal is indicated at 45 and is formed with a longitudinal slot 46 in the middle, such slot continuing with divergent slits 47 in the direction of one end of the seal. In the application of the latter to the tongue 40 the seal is mounted with the slot 46 over the headpiece 43. Since the slot is shorter than the headpiece, a blade 49 formed by the slits 47 is caused to flex as shown in Fig. 6 on the down pressure of the seal. This permits the seal to be pushed forward, that is, in the direction of the arrow in Fig. 6, to insert its rear end portion into the corresponding slot 42 to the extent shown, and then fully

into the slot, this allowing the blade 49 to be snapped into the other slot as shown in Fig. 7. The seal therefore becomes caught in the head-piece 43, locking the channel 21 from separation in respect to the channel 20.

It is now apparent that an unauthorized attempt to open the securing device will require tampering with or breaking the seal. However, when the mail bag has reached its destination, the breaking of the seal not only permits the device to open quickly, but at the same time procures the release of the rope sections 18 by the clamping tongue 38, so that the device may be readily drawn off the rope sections and the bag opened. The device thus forms an efficient and sturdy appliance for the purpose described; and being of a simple and compact nature, it may be produced at relatively low cost and handily carried or stored.

While I have described the invention along specific lines, various minor changes or refinements may be made therein without departing from its principle, and I reserve the right to employ all such changes and refinements as may come within the scope and spirit of the appended claims.

I claim:

1. A securing device for the rope sections extending from a tied mail bag comprising a member having a pair of openings for the inward passage of said rope sections, a further pair of openings for the outward passage thereof, means to clamp the portions of said sections which extend between the pairs of openings to said member, said means comprising a second member adapted to close on the first one for the operation of said means, a tongue extended from the second member through a slot in the first one, the emerging portion of the tongue being notched in its side edges to define a headpiece, a seal strip placeable on the first member and formed with a slot designed to receive said headpiece, and means carried by the seal strip adapted to flex upwardly and then downwardly to lodge the ends of the strip slot in the notches of the tongue.

2. A securing device for the rope sections extending from a tied mail bag comprising a channel shaped member, a pair of openings for the inward passage of said rope sections, a second pair of openings for the outward passage thereof, a pivot pin extending through the flanges of the channel shaped member adjacent one side thereof, a headpiece receiving slot adjacent the opposite end of said channel member, a second channel shaped member pivoted at one end on the pivot pin, an upwardly bent cord engaging tongue struck from said second channel, a second tongue having a headpiece bent upwardly from the forward end of said second channel, and a seal strip engageable with grooves in the headpiece to lock the pivoted channel in cord engaging position.

3. A rope locking device comprising an upper channel shaped member, a pair of oppositely disposed rope receiving holes in the top of the upper channel, a tongue receiving slot adjacent one end of said channel member, a pivot pin fixed between the channel sides, a lower channel fitting within said upper channel and pivoted to the pivot pin, a rope engaging tongue struck up from the lower channel and adapted to engage the rope between the tongue and the underside of the upper channel, an end tongue bent upwardly from the front of the lower channel, a headpiece on said tongue, and a seal strip engageable in slots in the headpiece to lock the lower channel in rope engaging position.

FREDERICK W. WOLF.
